Geo. H. Kimmel
ATTORNEY.

Patented Dec. 18, 1923.

UNITED STATES PATENT OFFICE.

HENRY C. RIEGE, OF KANSAS CITY, MISSOURI.

CEMENT-BLOCK MACHINE.

Application filed March 10, 1922. Serial No. 542,803.

To all whom it may concern:

Be it known that I, HENRY C. RIEGE, a citizen of the United States, residing at Kansas City, in the county of Jackson and State of Missouri, have invented certain new and useful Improvements in Cement-Block Machines, of which the following is a specification.

This invention relates to cement block molding machines, and has for one of its objects to increase the efficiency and utility of devices of this character.

Another object of the invention is to provide a device of this character, having means whereby blocks of various sizes and forms may be molded on the same machine.

With these and other objects in view the invention consists in certain novel features of construction as hereinafter shown and described and then specifically pointed out in the claims, and in the drawings illustrative of the preferred embodiment of the invention:

Figure 1 is a side elevation partly in section.

Fig. 2 is an end elevation.

Fig. 3 is a section on the line 3—3 of Fig. 1.

Fig. 4 is a plan view with the mold frame or box removed.

Fig. 5 is a plan view of the mold box illustrating one arrangement of the division members.

Fig. 6 is a transverse section on the line 6—6 of Fig. 1.

Figs. 7 and 8 are perspective views of the pallet member with two forms of core members.

The improved apparatus comprises a supporting frame including a platform or bed portion 10, supporting legs 11, and connecting rails 12 near the lower ends of the legs, the rails having bearings 13 to support transverse shafts 14 and 15.

The platform portion 10 is formed with a relatively large oblong opening indicated at 16 in Fig. 4.

The leg members 11 at each end of the frame are connected by transverse portions 17, and the latter connected by a strut or support 18 extending longitudinally of the frame. Stepped at their lower ends in the strut 18 are guide members 19, the latter supported at their upper ends in the platform 10 at each end of the opening 16.

Vertically movable on the guide members

19 is a follower member 20 having a plurality of sockets indicated at 21 in Fig. 4, the object to be hereafter explained.

The intermediate portions of the shafts 14 and 15 are preferably square or other form than round as shown, and mounted on the shaft 14 and rotative therewith are crank arms 22 and 23, in alinement longitudinally of the shaft, and mounted on the shaft 15 and rotative therewith are other crank arms 24 and 25, the latter at right angles to each other as represented in Fig. 1.

A link 26 is connected at its ends to the crank pin 27 of the crank arm 23 and a pin 28 supported by ears 29 depending from the follower member 20, while a similar link 30 is connected at its ends to the crank pin 31 of the crank arm 24 and a pin 32 supported by ears 32' depending from the follower member 20. Another link 33 is connected at its ends by the pins 34 and 35 of the crank arms 22 and 24, as shown.

One of the transversal shafts, for instance the shaft 14, is extended at one end to receive an operating lever 36, the latter mounted by a pin 37 to swing laterally to a slight degree on the shaft. Formed on the adjacent leg member 11 is a projection or stop lug 38 beneath which the lever 36 engages to lock the lever in its lower position, and thus hold the follower member in its elevated or highest position as shown in Figs. 1 and 2. By this arrangement it will be obvious that when the lever 36 is depressed and engaged with the stop lug 38 the follower member 20 will be uniformly elevated at both ends and locked in elevated position.

Laterally directed shelves 39 are attached to the platform 10 and supported by braces 40 in convenient position to support the detachable mold units, or the completed molded blocks, or the like.

Bearing upon the platform 10 is a pallet member 41 which also forms the bottom of the mold box, and is formed with a plurality of openings corresponding to the core members by which the openings through the blocks are formed and may be varied to any required extent as hereafter explained.

The mold box comprises side members 42 and end members 43, the end members having downwardly directed pins 44 which engage in sockets in the pallet 41, to hold the end members from lateral displacement.

The side members 42 are provided with stop lugs 45 at the ends against which the

end members 43 bear to prevent outward movement of the end members and longitudinal movement of the side members.

The side members 42 are likewise provided with notches to receive the bars 46, having a stop head 47 at one end bearing against the adjacent side member 42, and slotted at the other end to receive a wedge key 48 bearing against the other side member as shown. By this means the wall members of the mold box are firmly bound together and supported upon the pallet or bottom of the mold box.

The molded blocks are to be formed with various shapes of openings therethrough, and a plurality of the pallet members will be provided with each machine having openings corresponding to the core members by which the openings are formed in the block.

For the purpose of illustration two different arrangements of the core members are shown. In Figs. 5 and 7 a set of cores are shown to form a pair of blocks with their inner faces in flat V shape, and their outer faces parallel to the sides of the mold box and with openings therethrough with the sides of the openings in parallel relation to the faces of the blocks.

The core members to form the openings in the block are represented at 49 in Fig. 7, and are provided with dowel pins, indicated at 50, to enter certain of the sockets 21 in the follower member 20.

In Fig. 8 another set of the core members 49 are shown, and by providing a plurality of the sockets 21 in the follower member, cores of any required form and arrangement may be supported on the follower, as will be obvious.

The end members 43 of the mold box are preferably provided with inwardly directed ribs 51 whereby half channels are formed in the ends of the molded blocks, to receive binder portions of the cement in which the blocks are embedded when the walls are built up.

The cores 49 as represented in Fig. 7 are formed with recesses 52 to receive portions of the cement to constitute a binder portion to unite the walls of the blocks at one side to strengthen and support them and thus increase their resisting power.

The sides 42 of the mold box are formed with channels 53 centrally thereof, to receive the ends of a dividing member, indicated

by dotted lines at 55' in Fig. 5, to form half blocks, the dividing member 55' having ribs indicated at 54 to form cement receiving half channels in the adjacent ends of the half blocks.

The inner faces of the sides and ends of the mold box may be formed with configuration to represent ashler or quarry face, as indicated at 56.

It is obvious that the machine is capable of forming blocks having various forms of openings by providing cores corresponding in outline to the openings, and by multiplying the number and arrangement of the sockets 21 in the follower member, the various form of the cores may be easily supported by providing each core with dowel pins 50 to engage two or more of the sockets.

The improved device is simple in construction, can be inexpensively manufactured of any required material, and operates effectually for the purposes described.

The preferred embodiment of the invention is disclosed in the drawings and set forth in the specification, but it will be understood that modification within the scope of the claimed invention may be made in the construction without departing from the principle of the invention or sacrificing any of its advantages.

Having thus described the invention what is claimed as new is:—

1. In an apparatus of the class described a supporting frame, a follower member adapted to support core elements, shafts in spaced relation and each carrying a plurality of crank arms, connecting means between one of the crank arms of each shaft and the follower member, connecting means between the other crank arms, and means for rotating one of said shafts.

2. In an apparatus of the class described a supporting frame, guide members supported by said frame, a follower member adapted to support core elements and movable on said guide members, shafts in spaced relation and each carrying a plurality of crank arms, connecting means between one of the crank arms of each shaft and the follower member, connecting means between the other crank arms, and means for rotating one of said shafts.

In testimony whereof, I affix my signature hereto.

HENRY C. RIEGE.
